JAMES QUINN AND GEORGE W. PUTNAM, OF BOSTON, MASSACHUSETTS.

Letters Patent No. 86,446, dated February 2, 1869.

IMPROVED BOTTLE-STOPPER OR CAP.

The Schedule referred to in these Letters Patent and making part of the same.

To all persons to whom these presents may come:

Be it known that we, JAMES QUINN and GEORGE W. PUTNAM, of Boston, of the county of Suffolk, and State of Massachusetts, have invented a new and useful Improvement in Bottle-Caps; and do hereby declare the same to be fully described in the following specification, and represented in the accompanying drawings, of which—

Figure 1 is a side view, and

Figure 2, a vertical section of a bottle, with its metallic cap, provided with our invention.

Our invention consists of an improved cap or cover, to be applied to bottles, &c., such as are used for holding vinegar, pepper-sauce, catchup, sirups, molasses, or other liquids, or semi-liquids: and such cap is constructed as follows:

This cap; or cover, which is exhibited at A, is applied to the glass-bottle B, is so constructed that the liquids or semi-liquids will pass freely out without the usual difficulty which attends the operation of discharging the same, with caps, or covers, as they are usually made. This difficulty is caused mainly or entirely by want of vent for the air which is in the bottle.

When the bottle is at rest, the air being lighter than the liquid, takes position on top of the said liquid.

When the bottle is inverted, the air comes to the bottom part of the bottle, and, by reason of atmospheric pressure, it is found to be very difficult to eject the liquid contents through the discharge-tube or pipe placed, as it generally is, perpendicularly in the top of the cap.

In carrying out our invention, we have two pipes or tubes, *a b*, placed horizontally, one on each side of the cap or cover A.

The bottle, with our cap or cover, is therefore held in a horizontal position when pouring the contents, and the liquid runs out of the bottle through the pipe, on the lower side.

When the bottle is thus held horizontally, the air, of course, lies along the upper side of the bottle, above the liquid, and will freely pass in or out of the tube or pipe, on the upper side of the cap or cover, thus giving the bottle the air-vent which is needed; or, instead of having a pipe or tube placed on each side of the cap, or cover, a tube or pipe may be placed on one side only, and a vent-hole made on the opposite side of the said cap, or cover, the effect being substantially the same in both cases. This is shown in Figure 3, which is a section of a cap so made, *c* being the vent-hole, and *d*, the eduction-pipe.

In addition to the above, we arrange to have a perforated disk, or a strainer, *C*, of metal, or other suitable material, placed inside the cap or cover, or in the mouth or the neck of the bottle, such being to keep back the seeds, pulp, &c., of the pepper-sauce, catch-

up, &c., and prevent the same from clogging the discharge-tubes or pipes above named; or the said strainer may be made of wire or cloth, &c., as may be desirable.

In addition to the above, there may be a cover placed or screwed on the outside end of each discharge-tube or pipe, and this cover may be perforated, as shown at *d* in fig. 3, or otherwise arranged as a strainer.

If desirable, the tubes or pipes above-named may be inclined, or slightly elevated from a horizontal position, so that the liquids may not lodge in them, but run back into the bottle when the same may be at rest.

The ends of the above-mentioned tubes or pipes may also be provided with covers *ff*, to screw on, or to be otherwise fitted to them, if desirable, so as to keep out the dust, and prevent the evaporation of the contents of the bottle, when the same is not being used.

We are aware that a bottle-stopper, consisting of a common cork or plug, and two pipes or tubes passing lengthwise through it, is an old device, and consequently we make no claim thereto, our improvement having reference to a chambered cap, to screw or fit on the neck of a bottle, and such a cap we provide with vents, to lead out of its sides, and in opposite directions from the axis of the cap, and this cap we form with a shoulder arranged over its screw, in manner as represented in fig. 2, the purpose of the shoulder being to hold the strainer *C* in place in the mouth of the bottle, when the cap is screwed or fitted thereon.

By our arrangement of the air-vent with the discharge-tube, and so as to open out of the sides of the cap, there is little or no danger of any of the contents of the bottle getting into and passing through the air-vent while the bottle is in the act of being turned down to discharge its contents through the pipe *b*.

Thus it will be seen that our arrangement has important advantages over that where the two pipes lead lengthwise through a stopper, as in such case the liquid contents of the bottle are likely to be discharged from both of the pipes, unless great care is taken in turning down the bottle.

What, therefore, we claim, is—

The cap A, as chambered, and as having the air-inlet and the eduction-pipes *a b* arranged with respect to it and each other, viz., to lead laterally in opposite directions from and out of its sides, in manner substantially as described, such cap being either with or without a strainer arranged on it, as set forth.

JAMES QUINN.

GEORGE W. PUTNAM.
